UNITED STATES PATENT OFFICE.

WALTER L. LINDBLOM, OF McCACKEN, KANSAS.

SPINDLE-BEARING.

No. 829,165.

Specification of Letters Patent.

Patented Aug. 21, 1906.

Application filed December 4, 1905. Serial No. 290,236.

To all whom it may concern:

Be it known that I, WALTER L. LINDBLOM, a citizen of the United States, residing at McCracken, in the county of Rush, State of Kansas, have invented certain new and useful Improvements in Spindle-Bearings; and I do hereby declare the following to be a full, clear, and exact description of the invention, such as will enable others skilled in the art to 10 which it appertains to make and use the same.

This invention relates to bearings, and more particularly to those for cultivator-disks, and has for its object to provide a bearing which will be practically dust-proof and 15 which will be simple in arrangement and construction.

Other objects and advantages will be apparent from the following description.

In the drawings forming a portion of this 20 specification, and in which like numerals of reference indicate similar parts in the several views, Figure 1 is a side elevation of the present disk-bearing. Fig. 2 is an edge view of the disk. Fig. 3 is a central longitudinal section of the bearing on line 3 3 of Fig. 1. Fig. 25 4 is a cross-section on line 4 4 of Fig. 2, part of the flange, with a cap, being broken away to show the oil-feed screw. Fig. 5 is a detail sectional view of the oiling-plug.

Referring now to the drawings, there is 30 shown the usual supporting-shoe 5 for a disk 6. In the shoe there is secured a laterally-extending stub-shaft 7, which is surrounded by a circular recess 8, formed in the shoe, as shown. The disk 6 has a central opening 6', in which the stub-shaft is engaged for rotation of the disk thereupon, and a collar 9 is revolvably engaged with the shaft within the recess 8 and has a flange 9, to which the disk 40 is secured, the flange resting against the inner face of the disk, which is that face lying adjacent to the shoe. An outwardly-tapered spindle 10 is formed integral with the stub-shaft at the opposite side of the disk from the shoe, and at its inner end this spindle is provided with a circular flange 11, against which the disk rests. A plurality of bolts 12 are passed through the flange 9' and the disk and surround the flange 11, these bolts holding 50 the flange 9' to the disk.

A tapered boxing 13 is engaged revolvably upon the spindle 10 and has a laterally-extending flange 13' at its major and inner ends, this flange 13' resting upon the flange 11 and 55 having an annular flange 14 at its outer periphery which extends toward the disk and

incloses the flange 11, and this flange 14 has openings 15 formed therethrough which receive the bolts 12. Longitudinal slots 16 are formed in the boxing, and in the outer face of 60 the flange 13' there is formed a radial transversely-concaved recess 17, which opens through the outer periphery of the flange at one end and which communicates at its inner end with a larger recess 18, formed in the 65 flange and extending to the boxing. The recess 17 has half-threads formed therein, as shown.

A nut 20 is engaged with the stub-shaft 7 outwardly of the boxing, and engaged over 70 the boxing and the nut there is a solid cap 19, having a circular flange 21 at its inner end, which rests against the flange 13 and which receives therethrough the bolts 12, nuts being engaged with the bolt outwardly of the flange 75 21 to hold the several parts in position.

A recess 22 is formed in the inner surface of the flange 21, coinciding and registering with the recess 17 and having half-threads to form with the recess 17 a threaded passage, 80 and a recess 23, corresponding to the recess 18, is formed in the inner surface of the flange 21, communicating with the recess 22 and with the interior of the cap 19 and registering with the recess 18 to form an oil-chamber, 85 and this oil-chamber and the threaded passage lie between the flanges 13 and 21, as will be seen. An oil-feed screw 24 is engaged in the threaded passage and has an annular enlargement 25 at its inner end, which lies 90 within the oil-chamber formed by the recesses 18 and 22. A longitudinal duct 26 is formed within the screw 24, opening through the inner end of the latter, and at its outer end the duct 26 opens through one side of the 95 threaded portion of the screw, as shown. The arrangement is such that the screw may be screwed into the passage to bring the laterally-turned portions of the duct into the passage to prevent ingress of dust to the duct, 100 and the screw may be unscrewed to permit of the introduction of oil through the laterally-turned end of its duct. The bolts 12 may be loosened or tightened to vary the adjustment of the bearings, as will be readily understood. 105 The spindle 10 has an inward extension *a*, which is cylindrical in form and which is concentric with the stub-shaft and lies within the opening 6' of the disk 6 and within the collar 9, the collar and disk thus revolving upon the 110 spindle, which is hardened to minimize the wear.

What is claimed is—

1. In a disk-bearing, the combination with a support having a recess therein, of a stub-shaft engaged in the support and extending outwardly through the recess, a collar revolvably engaged with the stub-shaft within the recess, a disk revolvably engaged with the shaft at the outer side of the collar, said collar having a flange resting against the disk, bolts engaged in the flange and disk, a spindle carried by the shaft outwardly of the disk and having a flange at its inner end lying within the inclosure of the bolts, a longitudinally-slotted boxing revolvably engaged with the spindle and having a flange at its inner end, said flange having an inwardly-extending annular flange at its outer edge surrounding the flange of the spindle, said annular flange having openings in which the bolts are engaged, a cap engaged with the boxing and having a flange resting against the first-mentioned flange of the boxing, said bolts being passed through the flange of the cap, retaining devices engaged with the bolts outwardly of the cap-flange, said first-mentioned flange of the boxing and the cap-flange having an oil-chamber formed therebetween and having a threaded passage formed therebetween and communicating with the oil-chamber and opening through the outer peripheries of the flanges, and a screw engaged in the threaded passage, said screw having an enlarged inner end lying within the oil-chamber and having a duct opening through its inner end and through one of its sides, said screw being operable within the threaded passage to bring the opening in its side into and out of the passage.
2. In a disk-bearing, the combination with

a support, of a stub-shaft carried by the support, a disk revolvably mounted upon the stub-shaft, a spindle carried by the shaft outwardly of the disk and having a lateral flange at its inner end, a boxing revolvably engaged with the spindle and having flanges extending over the outer and peripheral faces of the spindle-flange, a cap engaged over the boxing and having a flange, bolts engaged in the disk, the flanges of the boxing and the flange of the cap, said boxing having longitudinal slots 50 therein, and means for admitting oil to the space between the boxing and the cap.

3. In a disk-bearing, the combination with a support, of a stub-shaft carried by the support, a spindle carried by the stub-shaft and having an annular flange between its ends, a disk revolvably engaged with the spindle between the flange and the support, a collar revolvably engaged with the spindle between the disk and the support and having a flange resting against the disk, a boxing engaged with the spindle outwardly of its flange and having flanges surrounding that of the spindle, a cap engaged with the boxing and having a flange resting upon one of the flanges 65 thereof, fastening devices engaged in the flanges of the collar, the boxing and the cap and in the disk, a nut engaged with the stub-shaft outwardly of the boxing and within the cap, and means for introducing oil between 70 the cap and boxing, said boxing having oil-passages therethrough leading to the spindle.

In testimony whereof I affix my signature in presence of two witnesses.

WALTER L. LINDBLOM.

Witnesses:

PERCY GRUMBEIN,
J. W. CHENOWETH.
